UNITED STATES PATENT OFFICE.

ARTHUR H. BLACKBURN, OF DOWNERS GROVE, AND FRANK E. FLEMING, OF CHICAGO, ILLINOIS, ASSIGNEES TO THE UNDERFEED STOKER COMPANY OF AMERICA, OF CHICAGO, ILLINOIS, A CORPORATION OF NEW JERSEY.

SIDE-DUMP STOKER.

1,364,237.

Specification of Letters Patent.

Patented Jan. 4, 1921.

Application filed November 12, 1918. Serial No. 262,251.

To all whom it may concern:

Be it known that we, ARTHUR H. BLACKBURN, a subject of the King of Great Britain, and FRANK E. FLEMING, a citizen of the United States, residing at Downers Grove, in the county of DuPage and State of Illinois, and at Chicago, in the county of Cook and State of Illinois, respectively, have invented certain new and useful Improvements in Side-Dump Stokers, of which the following is a specification.

Our invention relates to improvements in side-dump stokers and has for its general object to provide a fire-box floor construction of novel and advantageous structure. In an application, Serial No. 262,252, filed of even date herewith we have described an improvement in underfeed furnaces wherein certain floor plate structures between the retort and a side-dump closure, are tilttable laterally for effecting a side-spilling movement of the fuel-and-ash-bed. In some instances it is desirable to lighten the moving parts of a side-feeding floor-construction and rigidly to fix the major portion of the floor. These objects we attain in the embodiment of our present invention, which consists in the features of construction and arrangement of parts hereinafter more fully described and pointed out in the claims.

In the drawings wherein we have illustrated two available embodiments of our invention, Figure 1 is a fragmentary plan view of a portion of the fire-box floor and retort of an underfeed furnace; Fig. 2 is a transverse section on line 2—2 of Fig. 1; Fig. 3 is a view similar to Fig. 1 showing a modified structure embodying features of our invention; and Fig. 4 is a transverse vertical section therethrough on line 4—4 of Fig. 3.

Between the side wall 10 of the furnace and the retort 11 a partition or footing 12 may be provided, primarily to separate a side ash pit 13 from the wind box 14, the footing being supplemented as needed with a metal frame comprising the beam 15 and angle frame 16. The fixed portions of the floor structure may be rigidly mounted to span between the frame 16 and the suitably-fixed retort 11. Brackets 17 carry the rock shaft 18 for a side-dump closure or wing 19, a handle 20 beyond the front wall 21 of the furnace enabling the wing to be dropped

to dump its load into the ash pit below. Other ash disposal means, laterally spaced from the retort, may be employed if desired. The floor structure intervening between the wing 19 and the retort includes a series of fixed plates 23, preferably relatively short in the direction of length of the retort, and spaced apart somewhat to leave between them several transverse slots. In these slots are arranged tilttable fingers 24, pivoted on a shaft 25 that extends longitudinally of the furnace and is mounted in the front wall 21. Each of these tilttable fingers has an edge contour to conform, when the finger is lowered, with those surfaces of the plates that are presented toward the combustion chamber, and each has an arc-shaped inner edge 26 concentric with the shaft 25, so as to keep the slot closed when the finger is rocked on the shaft 25. The several fingers are connected respectively by links 27 to cranks 28 on a rock shaft 29 that is mounted in suitable bearings 30 on the partition beam 15, said rock shaft extending through the front wall and being provided with an operating handle 31 by which the fingers may be elevated, manually or automatically.

In the particular construction shown, and preferred, the retort 11 has a flaring lip partly afforded by the integral margin 11' of the retort and partly by the sloped inner ends of the fixed floor plates and through these ends are made twyers 32. Accordingly the fingers 24 preferably have inner end slopes corresponding with such lip contour, but they need not have twyers therein.

We prefer that the tilttable fingers 24 shall be confined to a zone relatively close to the retort, and that laterally beyond such zone of the fingers 24 there be a second zone of movable elements by which fuel, laterally displaced by the fingers, may be further fed laterally toward the dump-closure 19. As shown in Figs. 1 and 2, the construction provided with respect to the fingers 24 may be substantially duplicated in the second zone by arranging fixed floor plates 35 corresponding with the plates 23 and intervening fingers 36 movable between the plates. These fingers are mounted on a longitudinal shaft 37 at their outer edges and have their inner edges arc-shaped as at 38, so that they substantially maintain contact with the arc-

shaped outer edges of the fingers 24. Such outer fingers 36 are tilttable by means of links 39 and cranks 40 operated by the rock shaft 41 that is movable by a handle 42 at the front of the furnace. It is not necessary that the rocking fingers be provided in both outer and inner zones as hereinbefore suggested, and if confined to one of two parallel zones, such fingers may be in either thereof, though preferably this may be the inner zone. Thus, as shown in Figs. 3 and 4, the movable elements of the outer zone may be movable floor plates 35', rather than stationary ones operated by links and levers 15 and by rock shaft 41' after the manner of operation of the outer-zone fingers 36 hereinbefore described.

It will be apparent that by maintaining stationary the floor plates that are adjacent the retort and providing relatively narrow transversely extending tilttable fingers between such stationary floor plates, the moving parts are lightened and although the side-feeding effect is reduced somewhat, the 20 fingers serve adequately to remove or break up clinkers, and to move a material portion of the ash. Either construction shown will break up the portion of the fuel and ash bed at the edge of and laterally beyond the retort and will enable the operator readily to 25 clean the fire. It is preferable that the floor plates intervening between the fingers be provided with twyers 32 for supplying air to maintain some combustion in the zone of 30 operation of the fingers, and it will be apparent that the construction described practically insures against the total freeing of any plate portion of the structure from all 35 ash or fuel deposit so that the portions of the floor in which the fingers work are substantially insured against exposure to the full heat of the combustion chamber, and thereby the chance of warping or breakage of the floor structure is minimized. For 40 this reason it is preferable, if movement of large floor plates in one zone be desired, that such zone be the outer one as shown in Figs. 45 3 and 4. The constructions set forth enable even an inexperienced operator to clean the furnace readily without material likelihood 50 of waste due to the feeding of live fuel across the floor and through the dump opening.

While we have herein described in some 55 detail particular embodiments of our invention for purposes of full disclosure, it will be apparent to those skilled in the art that numerous changes in details may be made

without departure from the spirit of our invention within the scope of the appended 60 claims.

What we claim is:

1. In a furnace, the combination with a retort, means at the side and separated from said retort for disposing of ash, and an intervening floor section comprising fixed floor plates and side-dumping fingers disposed between said plates and extending transversely with respect to the retort, said fingers being tilttable to elevate their inner 65 retortward ends, and means for operating said fingers.

2. In an underfeed furnace fire-box floor structure, the combination with a retort, and ash disposal means paralleling said retort 75 and spaced therefrom, of intervening floor structure comprising a series of relatively short floor plates adjacent the retort, and intervening narrow, transversely-extending, movable fingers, between said plates, a pivot 80 shaft whereon the said fingers are mounted adjacent their ends that are remote from the retort, and means for rocking said fingers about said pivotal axis.

3. In an underfeed furnace fire-box structure, the combination with a retort and means spaced apart from said retort and paralleling the same for disposing of ash, of intervening floor structure comprising a plurality of series of laterally tilttable means, 90 and means for operating said tilttable means of each series independently of the other to feed fuel and ash laterally from the retort toward the ash disposal means, one said series of tilttable means comprising a plurality of fingers pivoted adjacent their edges that are remote from the retort, there being fixed floor plates intervening between 95 said fingers.

4. In a furnace of the character described, 100 the combination of a central retort, ash disposal means parallel therewith, floor structures up-sloping from said ash disposal means to said retort, and including relatively-wide fixed floor plates spaced apart, 105 lengthwise of the floor, and relatively narrow fingers arranged in the spaces between said plates, said fingers arranged in a plurality of tiers, a shaft for each tier of fingers arranged near the floor level and supporting the fingers of the tier near their outer extremities, and means for elevating the inner or retortward ends of the fingers. 110

ARTHUR H. BLACKBURN.
FRANK E. FLEMING.
